ATTORNEY

UNITED STATES PATENT OFFICE.

ANTONE E. WOLTER, OF OLYMPIA, WASHINGTON.

RACE KNIFE.

1,413,308.

Specification of Letters Patent. Patented Apr. 18, 1922.

Application filed June 19, 1918. Serial No. 241,070.

To all whom it may concern:

Be it known that I, ANTONE E. WOLTER, a citizen of the United States, residing at Olympia, in the county of Thurston and State of Washington, have invented a new and useful Improvement in Race Knives, of which the following is a specification.

This invention relates to new and useful improvements in race-knife instruments, and the object of this improvement is to provide, primarily, a race-knife susceptible of being utilized as one of the co-acting elements of a pair of dividers or spacing instruments, and which has a cutter member with a V-shaped blade suitable for the carving of grooves of an ornamental character in parts of furniture or the like.

A further object resides in the adaptability of this combination instrument to have its respective parts pivotally attached at one end upon a handle, whereby the same can be closed thereupon when not in use, for convenience in carrying.

The invention consists in the novel construction, adaptation and combination of parts as will be more clearly described in the following specification, illustrated in the accompanying drawings, and finally pointed out in the appended claim.

In the drawings, Figure 1 is an elevation of my combination instruments, Fig. 2 is a plan thereof, and Fig. 3 is a section of the pivotal attachment of the respective parts of the instrument upon a handle.

Referring more particularly to the drawings, in which like reference numerals indicate like parts, the numeral 1 represents a handle of suitable design and material upon which is pivotally attached at one end a pencil-holder 8 and a shank tool 2 having an extension 3 at an angle to the shank, and which extension has a flange bent up on a line longitudinally of this extension so that the like end of the extension and the flange, being sharpened, constitute a V-shaped edge 4.

Upon the shank 2 is provided a longitudinal slot 6 wherein is disposed a pointed projector 7 adapted to be movable longitudinally therein to extend outwardly as shown by dotted lines in Fig. 1. The function of this pointed projector is to coact with the pencil 7' carried by the holder 8 producing thereby a spacing instrument or dividers as

occasion demands, or to serve as a guide or gage whereby the incline of the cutter may be maintained without variation.

Both the pencil-holder and the race-knife are carried by the pivot 9 upon the handle and this pivot is designed to have a portion thereof of squared contour 10 to engage the correspondingly shaped hole in the handle so that the pivot will be precluded from turning when either the race-knife or pencil-holder is actuated. The thumb-nut 11 is provided to regulate the degree of frictional contact desired to hold the respective instruments from movement when set at a desired point.

12 is a slot provided in the handle 1 for the reception of the flange portion 3 of the race-knife, and 13 is an elongated slot extending rearwardly to a predetermined position on the handle in alignment with the slot 12. The provision of this latter slot is to afford space-way for the closing of the race-knife so that the flange 3 thereof will project within the slot 12, the blade portion 4 being protected from coming in contact with the surface of the knife handle at the side opposite the slot 12 and being dulled, by the shank 2 abutting the end of the slot 13 as shown by dotted lines in Fig. 1.

In using the instrument, the blade shank is opened up to a position where it can best be used and is fixed in this position by tightening the nut 11. The operator then grips the handle portion 1 and draws the cutter blade edge 4 against the piece being carved, which may be wood or other material used in making ornamental parts of furniture, and thus carves grooves therein as desired.

What I claim is new, and desire to protect by Letters Patent, is:—

In a race knife, a handle body provided at one end with an elongated slot and adjacent its opposite end with an aligned blade-receiving slot, a knife shank pivoted at its inner end within said elongated slot, said shank having an acute angled extension at its outer end forming a cutter that is movable into and from the receiving slot.

Signed by me at Seattle, Washington, this 7th day of May, 1918.

ANTONE E. WOLTER.
